FIG. 7

UNITED STATES PATENT OFFICE

FLOYD D. WENN, OF BINGHAMTON, NEW YORK, ASSIGNOR TO THE BREWER-TITCHENER CORPORATION, OF CORTLAND, NEW YORK, A CORPORATION OF NEW YORK

METHOD OF MAKING INSULATOR CAPS

Application filed September 26, 1928. Serial No. 308,375.

This invention generically relates to the art of hollow metal swaging, and more particularly pertains to an improved process for stamping up a shell-like socketed cap member affording a radially undercut mouth rim adapted to securely mount therein, an insulator disc of the suspension type as used in connection with high-tension electric transmission lines, switch stands or the like. 5 The primary object of my method is to effectively shape up in a cold state, a sheet-metal blank into an undercut chambered product of the character indicated, in which the wall thickness may be properly maintained when the dome thereof is extruded 10 to provide for a partitioned link chamber adapted to pivotally mount the cap attachment means therein.

Such protective cap is required to possess 20 the utmost of reliability as to structural material for the reason that it is both difficult and expensive to replace any defective insulator cap assembly, once it has been placed in service. The present invention seeks to 25 reduce factory costs and to promote a more uniform and reliable quality of such products as compared with the conventional cast type of insulator cap.

To this end and the accomplishment of 30 other new and useful results, my invention further consists in novel features of structure and manipulation, all of which will hereinafter be more fully described.

Reference is had to the accompanying one 35 sheet of drawings which are illustrative of a specific embodiment of my invention, in which like characters of reference indicate like parts, and in which:

Fig. 1 represents a fragmental portion 40 of a series of alternate insulator discs arranged in tandem, each such unit being interconnected by means of my interposed cap devices and the assembly primarily intended to suspend a high tension transmission line.

Fig. 2 cross-sectionally represents the 45 manner in which a sheet-metal blank is first to be drawn up into a cup-shaped structure having a flaring skirt portion whose rim terminates in a relatively small open mouth dimension.

Fig. 3 shows the cup mouth region crimped inwardly to provide for a radially undercut socket chamber adapted to receive and secure the neck of the insulator disc.

Fig. 4 indicates the method by which the 55 cup dome may be drawn to form a stepped crown plate intended for insulator support purposes, while Fig. 5 shows my partially completed cap provided with a turned concentric partition seat.

Fig. 6 is a cross-sectional view of a 60 concavo-convex style of metal expansion plug adapted to cooperate with said seat and seal said stepped crown plate with respect to the cup chamber proper to constitute a partitioned link chamber.

Fig. 7 illustrates the manner in which 65 the walls of my link chamber may be cut out into a socket type of insulator cap, with Fig. 8 showing a top view thereof as taken along 70 line 8—8 of Fig. 7.

Figs. 9 and 10 represent an alternate 75 method for shaping up said link chamber into complementary spaced ear straps for hanger attachment purposes.

Referring first to Fig. 1, this schematically represents a completely assembled insulator unit as ordinarily used in conjunction with a series of multiple insulators for suspending a high tension line from a transmission tower, or the like. A distinguishing feature of each such insulator unit resides in the use of an improved bell-shaped metal cap provided with flared tubular skirt portion B1 of which the annular dome portion B5 is stepped to provide for an outwardly offset crown portion B3, which in the present instance is shown as of the socket type adapted to receive the ball head of the support link C1. The mouth or lip edge of 80 said cap is equipped with an inturned rim B4 serving to snugly mount the neck A1 of the glass, porcelain or similar style of petticoat insulator disc A2. Said disc may be provided with a centrally disposed socket A3 85 into which the fixed shank end of the headed link-pin C1 may be firmly cemented or otherwise secured, while the insulator neck A1 may likewise be fastened into the radially undercut cap cavity, preferably by 90

95 100

means of cement or other suitable filler medium denoted by A4.

Taking up now the making of such a cap structure by my improved method, the first 5 step resides in stamping up by means of any suitable dies, a sheet-metal blank into the simple cup shaped structure such as is cross-sectionally represented by Fig. 2. The end in view is to fashion said blank into a shell-like member providing for a flared tubular skirt portion B1 of substantially straight-lined diverging profile; the larger open end portion thereof terminates in a trimmed or otherwise finished rim edge B4' that is 10 preferably brought up sufficiently to give the rim mouth a relatively small inside dimension. The opposite smaller end of said conical skirt is initially closed by a slightly dished transverse dome wall portion B5'. 15 For reasons that will appear presently, it is preferred to make the initial height "H" of the aforesaid cup skirt somewhat longer than the corresponding finished skirt dimension "h" of the completely fabricated cap 20 (see Fig. 5).

As a further step in the making of my insulator cap, said rim B4' may now be crimped inwardly in the manner disclosed by Fig. 3 to form a radially undercut groove portion B6 lying contiguous to the rim region. The dome element B5' may now be 30 drawn through the medium of one or more draw-ring devices, such for instance as the punch D1 and a cooperating bottom die D2. 35 These are adapted to progressively impart to the center region of said dome, an offset crown plate B3 adapted for cap supporting purposes. The semi-spherical crown portion thus formed is preferably so shaped as to 40 afford a peripheral sidewall element B3' adjoined bend to the remaining marginal portion of the annular dome wall B5. As applied to present purposes, the use of said ring die serves to crowd a surplus portion 45 of the original skirt length H inwardly while only partially drawing down the relatively flat center dome region without excessively robbing the metal therefrom or unduly thinning the resulting crown wall 50 formation.

An outstanding advantage gained by first forming up the simple cup-shape and then drawing an integral crown plate thereon, lies in the more uniform distribution of 55 metal throughout the finished cap product. The described forming steps are also relatively easy to perform in contrast to similarly shaping up in a single operation, the cap structure shown in Fig. 5; under the 60 latter conditions, the metal would be subjected to undue stretching strain and the dies far more likely to pierce the dome plate crown, especially so when applied to relatively heavy sheet metal blank such as must 65 necessarily be resorted to in fabricating in-

sulator caps of the heavy-duty suspension type. If desired, the aforesaid rim crimping operation may be performed subsequent to drawing the crown B3, but by following the stipulated sequence of operations, the shank of the punch D1 may be centered by the inturned rim in the manner indicated in Fig. 4.

The crown wall portion of my otherwise completed cap may now be punched or machined out in alternative ways to form up a compartmental link chamber B8 adapted for attachment of different styles of supporting links, one example of which is depicted in Figs. 7 and 8. By the use of suitable milling tools, this socket type of cap support, may be cut to provide for a key-hole aperture B9, whereupon the ball head of the link pin C1 may be pivotally inserted therein and secured against inadvertent displacement by the conventional cotter pin C2 or the like.

In the alternative cap support means illustrated in Figs. 9 and 10, the walls of said link chamber B8 may if preferred, be given a modified flattened shape which is cross slotted at B10 and the resulting complementary ear straps provided with extruded aligned apertures B11 adapted to mount the toggle pin B12 therebetween. Said pin engages a somewhat different type of support link pin C1' in that this is equipped with a journaled stub end enlargement of the conventional clevis type.

It now remains to provide for a weather-proof partition between the undercut skirted socket and the apertured crown portion of my cap. Referring to Fig. 5, it will be observed that a seating tool (shown in dotted outline) may be entered through the open mouth of the cap to countersink a cylindrical seat B13 within the rounded side-wall region lying inwardly of the circumscribing dome portion B5 as shown in dotted outline. Said annular seat is preferably sealed by a 110 separately formed expansion plug E such as is cross-sectionally detailed in Fig. 6 and in which the edge of the dished disc is initially given a true cylindrical rather than a conical shape; the edge of this convexo-concave partition disc may be inserted upon said seat in a snugly fitting relation with the dished crown of the plug faced toward the link chamber B8 and away from the in-turned cap rim B4. Said plug is thereupon 115 partially flattened in place by the use of suitable tools of which one may be entered through either of the cited crown apertures to make a weather proof plug joint in the manner represented in Fig. 7 or 9.

My invention in part resides in forming the outer incasing walls of either of such partitioned link chamber integrally with those of the bell-shaped skirt walls of my cap, thus affording a perfectly smooth ex- 130

terior surface that can readily be uniformly and flawlessly galvanized for rust prevention purposes. It is expedient to carry the lowermost depending portion of the aperture B9 or the slot B10 closely adjacent to the periphery of the plug E in order to freely drain any rain or accumulated moisture from the link chamber B8 or as a substitute therefor, a drain hole B2 may be resorted to. My method is specially intended to allow of economically fabricating a cap of this character on a productive scale and to provide for a cap that will be reasonably free from hidden defects or excessive waste when subjected to rigid inspection.

It will be understood that various changes in the structural details or mode of manipulation may be resorted to in carrying out the described method of making insulator caps or the like, and that while it is preferred to follow the operative steps as prescribed, the same results may also be obtained when the order thereof is partially reversed or otherwise modified, all without departing from the spirit and scope of my invention heretofore described and more particularly pointed out in the appended claims.

Claims:

1. The process of stamping from a sheet metal blank, a supportable cap of the undercut socket type adapted to mount on an insulator neck therein, said process including forming said blank into a cup shape comprising a tubular skirt portion of which one end thereof is initially closed by a transverse dome wall portion, and thereupon, further drawing the central region of said dome into a stepped crown plate and during which operation the overall length of said skirt is axially contracted by bending inwardly the dome end thereof to contribute metal for forming up the drawn crown portion.

2. The process of stamping from a sheet metal blank, a supportable cap of the undercut socket type adapted to mount an insulator neck therein, said process including forming said blank into a cup shape comprising a tubular skirt portion of which one end is provided with a mouthed rim while the other end thereof is initially closed by a transverse dome wall portion, then crimping inwardly the cup rim region to form an annular radially undercut groove therealong, and thereupon by the use of ring-die means introducing the punch member thereof through said grooved cup mouth in a centered relation to said crimped cup ring for the purpose of drawing out the central dome region into a stepped crown plate adapted for insulator cap support purposes.

3. The process of stamping from a sheet metal blank, a supportable cap of the undercut socket type adapted to mount an insulator neck therein, said process including

forming said blank into a cup shape comprising a tubular skirt portion of which one end is provided with a mouthed rim while the other end thereof is initially closed by a transverse dome wall portion, and which dome is subsequently drawn into a stepped crown plate and an interconnecting perimeter side wall, then countersinking a shoudered bored seat interiorly of said side wall, and thereupon mounting a concavo-convex sealing plug upon said shoulder, the edge of said plug being initially given a cylindrical contour and expanded into said bore.

In testimony whereof, I have herewith set my hand this 24th day of Sept., 1928.
